D. L. ADELSPERGER,
APPARATUS FOR TREATING COTTON SEED,
APPLICATION FILED JAN. 30, 1919.

1,326,888.

Patented Dec. 30, 1919.

Don L. Adelsperger ^{Inventor}

Staley & Norman ^{Attorneys}

UNITED STATES PATENT OFFICE.

DOW L. ADELSPERGER, OF SPRINGFIELD, OHIO, ASSIGNOR TO THE BAUER BROTHERS COMPANY, OF SPRINGFIELD, OHIO, A CORPORATION OF OHIO.

APPARATUS FOR TREATING COTTON-SEED.

1,326,888.

Specification of Letters Patent. Patented Dec. 30, 1919.

Application filed January 30, 1919. Serial No. 273,990.

To all whom it may concern:

Be it known that I, Dow L. ADELSPERGER, a citizen of the United States, residing at Springfield, in the county of Clark and State of Ohio, have invented certain new and useful Improvements in Apparatus for Treating Cotton-Seed, of which the following is a specification.

My invention relates to separators and more particularly to that class of devices known as beaters employed in the treatment of cotton seed after the same has been cut, to separate the meats from the hulls and lint.

The object of my invention is to provide improved means for beating and for keeping the screen of the beater free from clogging with particles of hulls and lint.

In devices of this character, to obtain the most efficient service, it is essential that all the material shall be acted upon all the time and to that end the means for agitating the material must cover the entire area within the machine; that is to say, the beater means must extend from the central driving shaft to contact with the screen; but owing to inaccuracies of workmanship, wearing of the shaft journals or the deflection of the shaft the relation of the beaters to the screen vary and to avoid damaging the screen I have devised beater means that under the centrifugal force of the driving shaft will keep in constant contact with the screen and yet will yield to meet the varying distance of the beater means in its relation to the screen. For the purpose of keeping the screen clean it has been common to provide brushes acting upon the outer surface of the screen. These brushes soon become clogged and lose their efficiency. Furthermore such constructions interfere with the structural frame and to build the frame within the screen prevents the beating means from covering the entire area within the screen.

My invention, as will more fully appear, by simple and efficient means, not only covers the entire area within the machine but also acts to keep the screen clean. The screening member is shown in the form of a cylinder; but the improvement may be employed with screens of less than a full circle.

Furthermore the screen may be rotary or not.

In the accompanying drawings:—

Figure 1 is a longitudinal sectional view of a device embodying my improvements.

Fig. 2 is a vertical section through the screen cylinder and the beater arm shaft, 60 showing some of the beater arms.

Fig. 3 is a detail of the outer end of one of the beater arms.

Fig. 4 is a section on the line 4—4 of Fig. 3.

In the said drawings, 1 represents the screen of the cylinder, 2 end rings, 3 intermediate rings and 3^a longitudinal strips which support the same, the end rings being mounted upon ball bearings carried by 70 the stationary supports, 4, in a manner common in machines of this character, such, for instance, as shown in Patent No. 1,183,110, dated May 16th, 1916. As is also usual in these machines, there is provided a longitudinally extending shaft 5 which carries a plurality of beater arms 6, but a few of these beater arms in the present case being shown, it being the practice to provide a great number of the arms arranged in comparatively close relation with each other. The shaft 5 is revolved in one direction by power applied to the pulley 7 and in the present machine the screen cylinder is revolved in the opposite direction by power 85 applied to the worm wheel 8 through the medium of the power driven worm 9.

As has heretofore been explained, it frequently happens that as a result of wear or other causes that the shaft 5 will become 90 in eccentric relation with the screen cylinder, as a result of which the beater arms, during one portion of their revolution, would come in contact with and injure the screen, while in other portions of their revolution they would be removed from the screen to such an extent as to interfere with their proper action upon the material. To overcome the difficulties resulting from this is the essence of my invention and the 100 means which I employ will now be described.

Referring more particularly to Figs. 3 and 4, the outer end of each beater arm, which is preferably flattened as indicated 105 at 6^a, is provided with an elongated opening or slot 10 through which is threaded a ring 11. In Fig. 2 the shaft is shown as eccentrically arranged with respect to the screen so as to illustrate the result of the 110

construction when such eccentricity occurs from the reasons before stated. As the shaft and beater arms revolve, the rings will swing or fly out by centrifugal force in contact with the screen so that they will be maintained at all times in contact therewith. At the same time the slotted openings 10 allow the rings to recede or move in the direction of the axis of the shaft to prevent injury to the screen in the event that the shaft should be rotated in a reverse direction, as sometimes happens, or to compensate for any other abnormal relation of the beater arms to the interior of the screen.

While in the present case the screen has been shown as applied to a rotary cylinder, the improvements are equally applicable to a stationary screen formed in half cylindrical shape.

Having thus described my invention, I claim:—

1. In a beater, the combination, with a screening member, of a rotary shaft hav-

ing a plurality of radially extending beater arms fixed thereon, each arm having an opening extending transversely to the movement of the arm, and a ring threaded through said opening to freely swing by centrifugal force and sweep the surface of said screen. 25

2. In a beater, the combination, with a screening member, of a rotary shaft having a plurality of radially extending beater arms fixed thereon, each arm having an opening extending transversely to the movement of the arm, and a ring threaded through said opening to freely swing by centrifugal force to sweep the surface of said screen, said opening being of sufficient 35 length to admit of the ring moving longitudinally on the arm to and from said screen. 40

In testimony whereof I have hereunto set my hand this 25th day of January, 1919.

DOW L. ADELSPERGER.

Witness:

CHAS. I. WELCH.
